UNITED STATES PATENT OFFICE.

EDWARD GEORGE KOTHE, OF PARKERSBURG, IOWA.

TOBACCO-PIPE.

1,052,349.

Specification of Letters Patent.

Patented Feb. 4, 1913.

Application filed March 4, 1912. Serial No. 681,376.

To all whom it may concern:

Be it known that I, EDWARD G. KOTHE, a citizen of the United States, residing at Parkersburg, in the county of Butler and 5 State of Iowa, have invented a new and useful Tobacco-Pipe, of which the following is a specification.

The invention relates to tobacco pipes, and the object is the provision of simple 10 means for rendering the bottom of the bowl of said pipe readily accessible for the purpose of cleaning the same, thus eliminating the disagreeable odors and secretions so common to the ordinary tobacco pipes.

15 A further object is to provide means whereby the pipe may be set aside for a considerable length of time and remain burning, so that it is not necessary to relight the same as is ordinarily the case.

20 With these and other objects in view, the invention may be best understood from the following detailed description, taken in connection with the accompanying drawing, wherein like reference numerals designate 25 corresponding parts in all the figures.

In the drawing:—Figure 1 is a longitudinal sectional view of a tobacco pipe provided with my improvements. Fig. 2 is a bottom plan view thereof. Fig. 3 is a detail 30 view of the false bottom or strainer plate. Fig. 4 is a detail view of the closure plate detached.

The usual pipe bowl 1 is provided with a shank 2 and may be of any well known 35 shape or construction. The bore 3 of the shank terminates at one end at the rounded wall of the bottom of the bowl and at the other end is in communication with the pipe stem 5 through the smoke aperture 6. Thus 40 far, the pipe is of the ordinary construction and may vary in size, shape and proportions.

My improvements consist in providing the relatively small opening or passage 7 45 through the bottom of the bowl in alignment with the longitudinal axis thereof. The opening 7 is substantially of the area of the smoke passage, and the pipe is provided with a flattened surface 8 on the exterior 50 of the bowl at and surrounding the bottom opening 7, to which flattened surface the closure plate 9 is pivoted by means of the small screw 10 or rivet. The door is shown as substantially oval in form and is made 55 of thin metal, though it may be made of any desired shape and material.

Centrally of the enlarged portion of the plate is a projection 11 formed by striking upwardly or inwardly the metal at the center of the closure plate, and the said projection 11 is so located as to engage and fit within the outer end of the opening 7 when the door is swung over the opening. A lug 12 provided at one edge of the plate serves as a thumb piece in swinging the same. It 60 will thus be seen that the closure plate may be held in a closed position through the engagement of the projection 11 with the opening 7, it being understood that the tension of the screw 10 is sufficient to insure 65 this engagement.

Slightly above the bottom of the bowl I provide a perforated strainer plate 13 to support the tobacco and to provide a chamber or space 14 for nicotin, saliva, etc., 75 which chamber may be readily emptied and cleaned through the opening 7 by means of a wire or other cleaning tool or device. This plate consists of a thin metal disk, perforated throughout and having its edge 80 bent upwardly, said edge, upon the disk being introduced into the bowl, impinging against the walls of the bowl and holding the said disk firmly in place. Some of the perforations open out at the periphery of 85 the plate so as to leave a ragged or toothed edge which is caused to bite into the wood of which the bowl is made, and thus serve to retain it from displacement.

The closure plate is adapted to be swung 90 away from the opening and into the plane of the lower face of the stem to serve as a support for the pipe with the bowl in an upright position and with the bottom opening 7 elevated above the supporting surface 95 upon which the pipe may be placed.

By leaving the closure plate open, the pipe may be set aside and the slight draft created will suffice to keep the tobacco burning for a considerable length of time, thus 100 obviating the excessive use of matches and the consequent trouble and annoyance thereof.

In Fig. 2, the plate is shown in dotted lines swung laterally to one side of the opening 7. The circular dotted line represents the circumference of the inner wall of the bowl.

What is claimed is:—

A tobacco pipe having an opening 110 through the bottom of the bowl substantially of the area of the smoke passage and

provided at the exterior of the bowl with a flat inclined face surrounding the bottom opening, a laterally movable substantially flat closure plate adapted to be swung away from the opening and into the plane of the lower face of the stem to serve as a support for the pipe with the bowl upright and with the bottom opening elevated above the surface upon which the pipe is placed to permit a draft through the bowl and to support combustion of the tobacco, said

plate having a projection struck inwardly from the center of the plate to engage in the said opening to hold the plate from lateral movement.

15

In testimony, that I claim the foregoing as my own, I have hereto affixed my signature in the presence of two witnesses.

EDWARD GEORGE KOTHE.
